United States Patent Office

Des. 181,811
Patented Dec. 31, 1957

181,811

DOOR ESCUTCHEON OR THE LIKE

Nolan Kent Rhoades, Beloit, Wis., assignor to National Lock Company, Rockford, Ill., a corporation of Delaware

Application September 30, 1955, Serial No. 38,188

Term of patent 14 years

(Cl. D50—6)

Fig. 1 is a front elevational view of a door escutcheon, showing my new design; and

Fig. 2 is a side elevation thereof.

I claim:

The ornamental design for a door escutcheon or the like, substantially as shown.
